UNITED STATES PATENT OFFICE.

JOHN L. NICHOLSON, OF CHICAGO, ILLINOIS, ASSIGNOR TO AMERICAN ARCH COMPANY,
OF NEW YORK, N. Y., A CORPORATION OF DELAWARE.

LOCOMOTIVE-FIRE-BOX ARCH.

1,229,393.

Specification of Letters Patent. Patented June 12, 1917.

Application filed March 15, 1916. Serial No. 84,466.

To all whom it may concern:

Be it known that I, JOHN L. NICHOLSON, a citizen of the United States, and a resident of Chicago, Cook county, Illinois, have invented certain new and useful Improvements in and for Locomotive-Fire-Box Arches, of which the following is a specification.

My invention relates to locomotive boiler furnaces and has special reference to improvements in the refractory arches of such furnaces.

It is well known that the inclined front arch as ordinarily installed in a locomotive boiler firebox performs the function of preventing the direct sweep of the flames from the fuel bed to the flues, thus increasing the length of the flameway and the heating effect of the walls of the firebox. It is also well known that such arches are effective in the matter of causing a more uniform action of the draft through the fuel bed. Indeed, whereas under the old practice it was necessary to bank fuel upon the forward end of the grate, it is now customary to bank the fuel upon the rear end of the grate to oppose the more direct lifting effect of the in-rushing air beneath the rear end of the arch. With the exception of cinder holes, which are often placed at the lower ends of such arches they are made as nearly as possible imperforate. I speak here of the general practice, and not of the few isolated examples appearing in prior art patents which show arches containing holes for the passage of hot air, or for the deflection of cinders, or for the direct passage of gases from grate to flues. It is also now a well recognized fact that the practical efficiency of a refractory arch is in direct proportion to the mass of refractory material therein.

The primary object of my invention is to so improve the construction of such refractory arches that it shall be practicable to increase the mass or volume of refractory material therein, and also the length of the arch. And further to provide an arch construction which shall present a large number of upwardly and laterally leading gas mixing ducts, which, being more or less uniformly distributed in the body of the arch, shall permit the firebox gases and products from each part of the grate to reach the combustion space above the arch by more di-

rect routes than around the rear end of the arch; and, whereby the products, after leaving the region of high temperature at the surface of the fuel bed shall be again subjected to a high temperature in the arch zone intermediate the grate and the flues, inasmuch as many of the products pass through the considerably elongated and restricted ducts or passages in the refractory body of the arch; and further whereby the arch is made to present a large number of vertically and laterally tortuous passages tending to divert or deflect the gases transversely in the firebox, thereby causing or setting up many cross currents in opposition to the longitudinally moving currents of gases from the rear end of the firebox and insuring the uniform mixing of the combustible gases and air in the combustion space above and forward of the arch. A further object of my invention is to construct an arch in such manner that it shall be self-cleaning, i. e., formed in the manner indicated above, and therefore characterized by the cross playing of conflicting streams of gases directly upon the top of the arch with the effect of preventing the lodgment and accumulation of cinders and slag thereon. My further purpose in the construction indicated is to provide for the heating of the top of the arch in quite as effective a manner as the bottom of the arch, to the end that the mass of refractory material shall to a greater extent perform the function of interchanging heat with the gases and products in the combustion space, prior to their entrance to the flues. Other objects of my invention, notably the improvement of the component bricks for arches of various kinds, will appear hereinafter.

The nature and broad characteristics of my invention as well as the novel forms and constructions, by means of which I attain the objects and results above stated, will be readily understood on reference to the drawings that form part of this specification, in which I have illustrated my invention in the best form which I have thus far devised.

In the drawings, Figure 1 is a longitudinal vertical section on the line Y—Y of Fig. 3, showing the rear end of a locomotive boiler and its firebox, containing a front arch embodying my invention;—Fig. 2 is an enlarged detail section thereof substantially on

the line X—X of Fig. 1;—Fig. 3 is a cross section on the line Z—Z of Fig. 1, showing my improved arch in course of construction;—Fig. 4 is an inverted plan view of one of the main or body bricks of the arch;—Fig. 5 is a perspective underside view of said body brick;—Fig. 6 is an inverted plan view of one of the marginal bricks of the arch;—Fig. 7 is a cross section similar to Fig. 2, but showing a modified form of my invention;—Fig. 8 is an underside perspective view of one of the body bricks shown in Fig. 7;—Fig. 9 is a further section like unto Fig. 2, and showing still another modification of the invention;—Fig. 10 is an underside perspective view of a body brick shown in Fig. 9;—Fig. 11 illustrates a modified form of said body brick;—Fig. 12 is a further modification thereof;—and, Fig. 13 is an underside perspective view of a body brick of the form shown in Fig. 2 but lacking the lower sockets.

The parts of the typical locomotive boiler firebox or furnace shown in the drawings may be identified as follows:—2, 3, and 4 are respectively the wrapper sheet, the throat sheet and the rear sheet of the boiler shell;—5 are the flues;—6 is the flue sheet;—and 6' the inner throat sheet;—7, 8, and 9, are respectively the rear sheet, the crown sheet and the side sheets of the firebox;—10 is the mud ring which joins the vertical walls of the boiler shell and firebox;—11, is the grate, and 12 is the fuel door of the firebox.

The familiar water-circulating arch tubes, 13, extend from the inner throat sheet, 6', to the upper part of the rear sheet, 7. They are spaced apart at distances fixed as herein-after explained. The outer tubes of the group are usually somewhat nearer the side sheets, 9, than to the intermediate tubes of the group. Groups of four tubes are shown in the typical cross sectional views. For convenience, I shall refer to the intermediate arch tubes by the number 13, and to the outer arch tubes by the number 13^a. These tubes, in conjunction with the side sheets, serve to support the component bricks and therewith complete the inclined arch.

As arches in this position are common, it is sufficient to point out that if the ordinary practice were followed the upper end of the inclined arch would not extend beyond the point indicated by the arrow, A, for it is ordinarily necessary to leave a large opening or gas passage between the upper end of the arch and the crown sheet, 8. Using my invention, it becomes practicable to extend the arch farther toward the crown sheet, 8, and rear sheet, 7, and to leave only a comparatively small passage, B, between the rear end of the arch and said sheets. By so doing I obviously greatly increase the

mass of refractory material which is present in the firebox for purposes of heat-storage and interchange and to deflect the gases from the fuel bed toward the rear end of the firebox, to insure a proper distribution of heat upon all of the walls thereof. I should not be able to so greatly increase the extent and the mass of the refractory material were it not for the fact that I provide auxiliary gas passages in the body of the arch, and thereby compensate for the restriction of the passage, B, at the rear end of the arch. The auxiliary passages referred to are of peculiar form, to the end that their use shall not entail complications in either the making of the brick or the building of the arch, and to the further end that the gases instead of being permitted to move all in a general longitudinal direction in the firebox, shall be largely dispersed in lateral directions as they pass from the fire-chamber, F, into the combustion chamber or space, C.

As explained hereinafter, I prefer that the component bricks shall themselves contain and form the auxiliary passages; and that this advantage shall be secured without entailing the use of body bricks of more than one pattern or design. While this is my preference, I have nevertheless illustrated several modified forms of the arch, 95 composed of several kinds of bricks.

It is very desirable that the component bricks shall be adapted to adjust or accommodate themselves to irregularities in the supporting tubes, and always retain firm seats thereon. To this end I have invented special arch bricks which contain the auxiliary passages described, and yet present three point bearings upon the tubes, so that they are not detrimentally affected by irregularities in their supports.

Referring now to Figs. 1, 2 and 3. It will be seen that the arch is composed of several longitudinal rows of bricks separated from one another by the arch tubes which support them. Where there are four arch tubes there are three longitudinal rows of main or body bricks, 14, and two rows of marginal bricks, 15. The body bricks of each row abut side to side. Their ends bear upon the arch tubes. The marginal bricks are similarly arranged side to side and they extend from respective arch tubes to respective side sheets, preferably in the inclined positions shown.

I prefer that all of the body bricks, 14, shall be of one pattern, and hence interchangeable. As hereinafter stated, I shape them so that they may occupy either of two positions, one an elevated position and the other a depressed position, upon their arch tubes. Likewise, I prefer that all of the marginal bricks, 15, shall be of the same size or pattern. A detailed description of one body brick 14, will serve for all of the body

bricks; and, similarly a detailed description of one marginal brick will suffice for all of them.

Chiefly for convenience in manufacture, 5 not necessarily, I provide the brick, 14, with a flat top, 14^a; and the bottom, 14^b, is preferably parallel therewith. The thickness of the brick is determined by the dimensions 10 and height of the passages or recesses, 14^c, 14^d, therein. The recess, 14^c, opens only through the bottom and end of the brick, whereas I prefer that the opposite shall be divided into two parts, 14^a, 14^d, opening through the sides of the brick as 15 well as through the bottom ends thereof. A portion of full thickness remains between the recesses.

The passages are of less than one-half the length of the brick and are of less width 20 than the brick. Thus the bottom, 14^b, is of a Y formation or shape. I shall refer to the portion, 14^c, as the stem of the Y shaped bottom and to the portions, 14^a, 14^d, as the arms thereof. One reason for shaping the 25 brick in this manner is to insure the even shrinkage of the brick and to prevent the checking or cracking thereof during the firing process in the kiln. A second reason for so shaping the bottom of the brick is to 30 provide it with three points of bearing upon the arch tubes which support it. The ends or terminals of the parts, 14^c, and, 14^d, form such bearings and allow the brick to accommodate itself to, and rest firmly upon, arch 35 tubes which may or may not be in strict parallelism.

Two bearings or sockets, 14^e, and, 14^f, are provided in each of said terminal positions. The distance between the sockets 14^e, 14^f, is 40 such as to allow the relatively overhanging ends, 14^c, of the brick to rest upon the tops of the arch tubes; while the distance between the sockets, 14^e, 14^f, is so much shorter that when they are used the brick 45 is elevated upon the tubes. In the lower or depressed position, the ends of the passages, 14^c, and, 14^d, are closed by the tubes. The elevation of the brick upon the sockets, 14^e, opens or exposes the ends of the recesses, 50 14^c, and, 14^d, above the top of the tubes. The latter condition is depicted by the middle brick, 14, in Fig. 2. The outer bricks, 14, (which rest upon the tubes, 13, 13^a), depict the depressed condition, in which the 55 passages are closed.

The use of bricks, 14, all of one pattern or size, in the manner shown, is permitted by the depicted spacing of the arch tubes. It will be noted that the middle tubes, 13, 60 are closer together than the tubes, 13, 13^a. Thus the tubes 13, 13^a, are adapted to support the middle brick in elevated position with its ends overlapping the bricks (14), which rest upon the tubes, 13, 13^a. With 65 the bricks in these positions the passages

of the middle brick are open, and permit the upward and lateral movement of gases through the body of the arch.

The component bricks are of sizes which permit them to be passed through the fuel 70 door, 12, and from this fact it will be understood that the passages, 14^c, and 14^d, are relatively minute and are not only constricted but are also tortuous and cause the subdivision, deflection and flow of the products toward the side sheets above the arch. 75

The extreme ends, 14^c, of the bricks, 14, are preferably beveled inwardly to limit the end contact between the bricks as they rest upon the tubes. 80

It will be understood that the bricks are assembled upon the arch tubes in the manner shown in Fig. 3, so that the partial passages, 14^d, on one brick are completed by the like passages, 14^d, of the adjacent bricks. 85 However, no serious difficulty will be encountered when the bricks are indiscriminately assembled; for the side, 14^c, of any brick may quite as well serve as the side wall or closure of the partial passage or 90 half cavity, 14^d, of any other brick.

While my invention is not limited to the use of marginal bricks, 15, which are similar to the body bricks, I nevertheless much prefer to relieve the pressure at the sides of the fire-box by providing similar tortuous openings or passages through the marginal bricks. Thus each marginal brick, 15, is characterized by a Y-shaped bottom, 15^a, a main recess or passage, 15^b, and end recesses, 15^c, 15^d. I prefer that the brick shall taper toward and rest upon the side sheet, 9. The end, 15^d, of the brick, should be rounded or pointed to limit the end bearing of the brick to the stem, 15^e, i. e., to 95 substantially a single point of bearing on the side sheet, as shown in Fig. 6. The arms, 15^f, of the Y-shaped bottom provide the other two points of bearing, as upon the tube, 13^a. As shown, the recess, 15^b, opens 100 above the tube, 13^a, and above the top of the body brick, 14, which rests thereon, in manner to cause the gases from the fire-chamber, F, to sweep laterally across the top of the arch. 105

The positions of the bricks, 14 and 15, and their relations to the side sheets and arch tubes of the firebox, and also the manner of constructing the arch, are so well shown in Fig. 3 that further description 110 thereof seems unnecessary. 115

The irregular line, F', in Fig. 1, represents the surface of the bed of fuel on the grate, 11. During the operation of the locomotive there is a partial and fluctuating 120 vacuum in the firebox. As the products rise from the fuel bed the arch, as a whole, tends to deflect them toward the rear end of the arch. But, while the main sweep of the products is rearward and upward 125 130

around the rear end of the arch, there is at the same time a continuous flow of products through the described tortuous passages in the body of the arch. The streams which emerge from the passages in the arch sweep the top of the arch and prevent the lodgment of cinders thereon and also forcibly admix with the main stream moving forward from the passage, B. In this manner three principal operations are performed: First, the partial vacuum, or low pressure, is equalized throughout the fire-chamber, F;—second, the combustibles and air are forcibly admixed in and upon the underside of the arch and in the passages thereof;—and, third, the many streams of combustibles and air are violently admixed in the combustion chamber, C.

The movement of the flames from the firebox through the body of the arch, insures the uniform heating of the refractory material and a measurable improvement in the constancy of temperature in the combustion chamber, C. The marked increase in the mass of refractory material made possible by the relief of pressure through the body of the arch results in maintaining a more constant temperature throughout the firebox and in relieving the flues from the detrimental effect of the cold air which is admitted when the fire door, 12, is opened. The equalization of pressure in the fire-chamber, F, allows the carrying of a fuel bed which is comparatively thin and of uniform depth, with a consequent increase of efficiency.

My invention may be carried out with refractory bricks of different shapes. The middle brick, 17, and the marginal bricks, 18, shown in Fig. 7 are of the now well known "Security" types. The bricks, 19, 19', are of a special type which I have invented for use with such bricks. The bricks, 19, are characterized by arch tube bearings, 19', and by preferably symmetrical, tortuous gas passages, 19", which open above said sockets and the supporting tubes. The bricks of this form of perforated, gas mixing arch are assembled in much the same manner as shown in Fig. 3 and the streams of gases which emerge from the passages, 19", obviously sweep transversely across the top of the arch.

In the further modification shown in Fig. 55 I employ bricks, 19, of the form next above described, for the middle row, and substitute modified bricks, 20, in the outer rows. Inasmuch as the passages, 19", of the bricks, 19, must remain open, bricks, 20, are provided with low ends, 20', adjacent thereto and with high ends, 20", distant therefrom, the latter containing the essential passages, 20". The low end of the brick, 20, may be formed upon an incline, 20", to wedge 65 against the middle arch tube, 13, or may be

provided with a socket, 20", as shown in Fig. 11. The outer end of the brick may contain either one socket, 20", as shown in Fig. 11, or two sockets, 20" and 20", as shown in Fig. 12. Obviously, the entire body of the arch may be made of the bricks, 20. I prefer that the brick, 20, shall be both strengthened and reduced in weight by the addition of inner-end recesses, 20", best shown in Fig. 10, but if desired these may be merged with the recess, 20".

The brick, 14" shown in Fig. 13, needs no description beyond the fact that it is substantially identical with the bricks, 14, of Fig. 2 except that it is of less thickness; as though the bottom part of the brick, 14, (Fig. 2) were removed to the level of the horizontal dotted line at the left hand of Fig. 2. Such bricks can very well be substituted for the body bricks shown in Fig. 2.

In further elucidation of the subject, the following matters may be mentioned:—

This form of arch will increase the mass of refractory arch material, thereby increasing the regenerative action of the arch and 90 maintaining a higher and more uniform temperature in the firebox.

The form of brick used allows the combustible gases to pass through the openings of the brick in small streams and to commingle above the arch, thereby insuring a more intimate mixture of the different combustible gases with the oxygen present; and a more perfect combustion, with an attendant saving in fuel and an increase in boiler 100 efficiency.

The openings provided in these special bricks more uniformly distribute and equalize the draft over the entire surface of the fuel bed. This equal distribution allows 105 the maintenance of a fuel bed of uniform thickness instead of the usual practice of banking the fire to suit the draft distribution, thereby increasing the flow of air through the grates and fuel bed with an attendant increase in temperature.

This uniform distribution of draft over a fire bed of uniform depth will result in reducing the pressure drop between the ash pan and firebox, and cause a reduction of 115 cylinder back pressure (required to produce the draft) with a consequent increase in the power delivered by the cylinders and increase in engine efficiency.

The light fuel bed of uniform thickness 120 which is made possible by this uniform distribution of draft will tend to eliminate "holes" in the fuel bed, and thus prevent the inrush of cold air which often results in flue leaks and engine failures.

The uniform distribution of the lighter draft makes it possible to burn the finer particles of coal on the fuel bed, thereby decreasing the losses due to incomplete combustion of carbon and cinders; and a reduc-

tion in amount of cinders discharged from the stack and accumulated in the smoke box.

The flow of gases through the openings provided by these special bricks, results in counter currents sweeping over the top of the arch in such manner as to prevent accumulation of cinders or slag on the top of the arch, thereby preventing the plugging of the lower flues, as often occurs with the present form of arch for the cinders and slag carried are swept up by these counter currents, carried through the flues and discharged at the stack.

15 The special bricks herein described will be found to be comparatively inexpensive and extremely strong and durable. Still other advantages will be apparent to those who are skilled in the art.

20 Having thus described my invention, I claim as new and desire to secure by Letters Patent:—

1. A locomotive boiler firebox, in combination with a refractory arch extending upwardly and rearwardly from the lower part of the flue sheet of the firebox to a point which restricts the opening between the arch and the crown sheet to an area not exceeding and preferably less than the aggregate area of the flues and said arch containing preferably uniformly distributed upwardly and transversely extending passages whereby the lack of area in the passage at the rear end of the arch is compensated and the 25 products from the fire chamber are subdivided into conflicting longitudinal and transverse streams in the space above the arch and rearward of the flue sheet.

2. A locomotive boiler firebox in combination with a refractory arch extending upwardly and rearwardly from the lower part of the flue sheet of the firebox and containing preferably uniformly distributed upwardly and transversely extending passages whereby the products from the fire chamber are subdivided into conflicting longitudinal and transverse streams in the space above the arch and rearward of the flue sheet.

3. A locomotive boiler firebox and its arch tubes, in combination with a refractory arch extending upwardly and rearwardly from the lower part of the flue sheet of the firebox and composed of rows of bricks resting upon said tubes and containing preferably uniformly distributed upwardly and transversely extending passages whereby the products from the fire chamber are subdivided into conflicting longitudinal and transverse streams in the space above the arch and rearward of the flue sheet.

4. A locomotive boiler firebox and its arch tubes, in combination with a refractory arch in said firebox and composed of high and low rows of bricks resting upon said tubes and the high bricks having openings in

their ends, whereby some of the products from the fire chamber are allowed to pass through the arch and conflicting longitudinal and transverse streams are set up in the space above the arch and rearward of the flue sheet.

5. A locomotive boiler firebox and longitudinal arch tubes therein, in combination with a refractory arch composed of longitudinal rows of bricks resting on said tubes, alternate rows of said bricks being elevated above the others and containing upwardly and transversely extending passages whereby the lack of area in the passage at the rear end of the arch is compensated and the products from the fire chamber are subdivided into conflicting longitudinal and transverse streams in the space above the arch.

6. The improved arch component brick herein described having two arch tube sockets in its end, one above the other, and both opening downward.

7. The improved arch component brick herein described having two arch tube sockets, one above the other, in each end, all opening downward.

8. The improved arch component brick herein described having two arch tube sockets in its end, one above the other, and opening downward, and said brick also having a cavity opening through its end and bottom.

9. The improved arch component brick herein described having open cavities in its bottom, one of said cavities in one end and two of said cavities in the other end, all 100 said cavities opening through the respective ends of the brick.

10. The improved arch component brick herein described having a Y-shaped bottom.

11. The improved arch component brick herein described having a Y-shaped bottom 105 and presenting three bearings for engagement with spaced supports.

12. The improved arch component brick herein described having a Y-shaped bottom 110 and containing gas passages at the side of the stem of its Y-shaped portion, and a single gas passage between the arms of said portion.

13. The improved arch component brick 115 herein described having a Y-shaped bottom and containing gas passages at the side of the stem of its Y-shaped portion, and a single gas passage between the arms of said portion, said passages opening through respective ends of the brick.

14. The improved arch component brick herein described having a flat top and a Y-shaped bottom, the latter containing gas passages which open through respective ends of 125 the brick and the brick being provided with arch tube bearings at the ends of the arms and stem of its Y-shaped bottom.

15. The improved arch component brick herein described having a flat top and a Y- 130

shaped bottom, the latter containing gas passages which open through respective ends of the brick and the brick being provided with two arch tube bearings at the end of each 5 arm and stem of its Y-shaped bottom.

16. A locomotive boiler firebox, in combination with a refractory arch extending upwardly and rearwardly from the lower part of the flue sheet of the firebox to a point 10 which restricts the opening between the arch and the crown sheet to an area less than the aggregate area of the flues and said arch

containing preferably uniformly distributed passages whereby the lack of area in the 15 passage at the rear end of the arch is compensated and the products from the fire chamber are subdivided into conflicting longitudinal and transverse streams in the space above the arch and rearward of the flue sheet.

20 In testimony whereof, I have hereunto set my hand this 19th day of January, 1916.

JOHN L. NICHOLSON.
